[57] CLAIM

The ornamental design for a tree trunk protector, as shown and described.

DESCRIPTION

FIG. 1 is a perspective view of the tree trunk protector showing my new design;

FIG. 2 is a rear elevational view thereof;

FIG. 3 is a front elevational view thereof;

FIG. 4 is a top plan view thereof;

FIG. 5 is a bottom plan view thereof;

FIG. 6 is a rear elevational view, shown in a flat stored position and broken away for convenience of illustration;

FIG. 7 is a front elevational view thereof;

FIG. 8 is a right side elevational view, shown in a flat stored position;

FIG. 9 is a left side elevational view thereof;

FIG. 10 is a top plan view, shown in a flat stored position and broken away for convenience of illustration; and,

FIG. 11 is a bottom plan view thereof.

The broken lines showing environment in FIG. 1 are for illustrative purposes only and form no part of the claimed design.
